J. I. COMBER

DEVICE FOR THE PROMOTION OF PIETY, RELIGIOUS DEVOTION,
AND HIGH IDEALISTIC SENTIMENTS

Filed July 5, 1922

UNITED STATES PATENT OFFICE.

JOSEPH I. COMBER, OF PHILADELPHIA, PENNSYLVANIA.

DEVICE FOR THE PROMOTION OF PIETY, RELIGIOUS DEVOTION, AND HIGH IDEALISTIC SENTIMENTS.

Application filed July 5, 1922. Serial No. 572,982.

To all whom it may concern:

Be it known that I, JOSEPH I. COMBER, a citizen of the United States, residing at Philadelphia, in the county of Philadelphia and State of Pennsylvania, have invented a new and useful Device for the Promotion of Piety, Religious Devotion, and High Idealistic Sentiments, of which the following is a specification.

10 It is a well established psychological truth that contemplation of artistic representations—paintings, statuary, monuments and the like—portraying or typifying historical, ecclesiastical and other celebrated events has 15 an unfailing tendency to arouse and excite in the human heart ennobling and pious sentiments of more or less intensity.

My invention relates to an artistic representation of this character and has for its 20 objects to provide an ornate, compact and economical structure for housing and successively displaying illuminated pictures and views depicting religious scenes and events in combination with wordings and texts appropriate thereto, printed or embossed in 25 classic style such as church text or other ecclesiastical type of lettering on the exterior of said housing, and simple and positive means for causing the pictures to be rotated 30 as desired by hand operation.

The general idea consists in assembling and systematically arranging a collection of idealistic pictures so as to portray and successively develop the sentiments to be 35 aroused; enclosing this collection in an ornate housing having one or more openings in the nature of windows through which the pictures may, one by one, be viewed; embellishing the housing with artistic inscribed texts appropriate to the pictures and 40 providing means to circulate the pictures past the openings and means to correctly illuminate them when so exposed.

I attain these objects by the means illustrated in the accompanying drawings, in which—

Figure 1 is an exterior side elevation of one half of the device; Fig. 2, a similar view of the other half; Fig. 3, an elevation in section, through the center, as shown by line 3 x 3, Fig. 4; Fig. 4, a plan view of the base and actuating mechanism; and, Fig. 5, an elevation, partly in section, of a modified form of the superstructure.

Similar indices refer to similar parts throughout the views.

The base, 10, is an ornamental pedestal provided with a circular chamber, 101, in which the hand operated mechanism to rotate the pictures is contained. Extending vertically from the center of the floor thereof is a fixed shaft or pin, 11, terminating in a pointed bearing, 111; and also pivoted to the floor at 121 near the circular wall, 102, is a lever, 12, extending across the chamber and passing through a horizontal slot, 103, in the opposite side of the wall so as to extend beyond the periphery of the superstructure, 16. This lever through the stress of spring 122, secured to pin 123 from the floor, is normally held out of the diametral line of its pivot and the shaft 11 and is restrained as desired by one side of the slot 103. This lever takes an upward course through the vertical slot 104 so as to project above the base and terminate in a small spatulated handle 124. Secured to the outside of the base adjacent to one end of the vertical slot 104 is a rigid member, 105, similarly spatulated and so positioned with relation to the upstanding movable lever end, 124, as to afford a convenient gripping means for the thumb and index finger whereby the lever may be drawn across the length of the slot 103.

Centered rigidly on the picture-bearing member, 15, on a vertically extending skeleton frame rotatable on the point 111, is an inverted crown-wheel, 14, having ratchet teeth 141. The axis of this wheel is bored to freely rotate about the shaft 11, the height of which is such that when the frame is pivoted on the bearing 111 the teeth 141 lie in a horizontal plane just above the plane of oscillation of the lever 12. Secured in this lever is a vertically movable self-springing actuating pawl, 125, so positioned as to normally press upwardly against teeth 141 and be engaged therewith. Another spring pawl, 126, to prevent reverse action of the wheel, is pinned at 127 to the floor so as to also engage these teeth. The amplitude of entire oscillation is limited by the slot to the exact extent required to rotate the wheel 14 the distance between adjacent teeth. As the drawing shows the device as a hexagon, this distance is one-sixth circle, required to change the pictures. The parts shown in

full lines in Fig. 4, indicate their normal position, and the broken lines, their position when members 124 and 105 are being pinched together.

5 The picture-bearing vertically extending frame, 15, is retained upon the pivot 111 through the agency of an axial inverted conical depression 151, whereby the frame rotates with extreme facility, for in the center of the top is another conical depression, 157, into which fits a dependent axial pivot point 131 from the top of the housing. As illustrated, each of five of the faces of frame 15 is divided into three openings, 153, in vertical tiers, and the sixth side is open entirely to provide for the installing of the luminary, 18, which may be an electric light, oil lamp, or candle. A long-time slow consumption wax candle, secured in socket 181, 20 and safeguarded by a mica chimney 182, is shown to illuminate the translucent pictures, which are mounted across the openings 153.

The housing forming the visible exterior portion of the body of my apparatus is a 25 columnar structure, rotatably fixed on the base and consists of a sheathing 167 secured to the frame, 16. This frame is similar to frame 15, but of course larger to permit rotation thereof, and contains corresponding 30 openings 162 and 163, over most of which the sheathing is applied. As illustrated, this covering is in the form of rectangular tablets containing the reading matter. Certain of the smaller openings, 162, are left 35 open to form frames for the underlying pictures, and the large opening 163 is completely covered by a full length inscribed panel hinged at 164 and provided with a knob 165, to serve as a door to the interior. 40 The lower portion of frame 16, is formed so that the polygon is reduced to a circle and a small portion of this circle bent out to form a horizontally extending flange—a ring circumscribed about the prism. This 45 ring or flange fits snugly but rotatably between a circular wall 166 formed by a depression in the base and the chamber wall, 102, already mentioned, over which it is telescoped. The entire structure is thus 50 rotatably secured beneath a thin annular member, 106, secured to the base by screws. The ornamental sheathing 167 is so applied as to leave upper and lower ventilating apertures, 161, to afford ample draft for an oil lamp 55 or a candle.

The cover, 17, consists of a pavilion-roof shaped cap with a hollow upstanding central stem, 171, which is screwed into the frame 16. It is vertically penetrated by the central pin 131 the lower end of which forms upper axial bearing for frame 15 as already described. This pin is fast to the extreme top-piece, 13, another quite small pavilion-roof device, and is so threaded as to be screwed through the center of the

cover at 172, which arrangement affords means for attaching the top as well as providing for the adjustment of the pivotal bearings.

In the modified form shown in Figure 5 70 the use of transparent or translucent pictures is obviated, as the lighting thereof is afforded by one or more small incandescent bulbs, 19, positioned adjacent the orifices 162 through which the pictures are viewed, and 75 the whole set of pictures may be imprinted upon light sheet metal, properly shaped to be used in lieu of frame 15. Similarly the outer housing, 16, is shown imprinted and formed, with the windows and doorway 80 stamped out of sheets, to the interior of which the electric lamps are attached. In other respects, the construction and operation are as already described.

The object in having the exterior super- 85 structure rotatable either way in the base is, to afford means for adjusting the view windows, 162, of any face of the prism with relation to the hand controlled parts, 124 and 105, so that the base may always remain in 90 any desired position. The necessary rotation is facilitated by the handles, 169, extending from the outside walls.

For the purpose of illustrating my invention I have shown and described a form 95 thereof at present preferred by me although it is to be understood that the divers instrumentalities of which my invention consists can be variously arranged and organized, and that the invention is not limited to the 100 precise arrangement and organization herein shown and described, and that I hereby reserve the right to re-organize and re-arrange these instrumentalities within the scope of 105 my claims. The form of my invention shown and described herein affords an admirable medium to apply to and illustrate the well known devotion of The Rosary which concentrates attention on fifteen events of 110 sacred history. In this devotion these events are styled the Fifteen Mysteries, and are divided into three groups of five each. The first group is called the Joyful Mysteries 115 and is set forth by five pictures which successively appear at the uppermost opening or window located at the top of the left hand face of Fig. 2. The second group—the Sorrowful Mysteries—is pictured around the middle tier of member 15 and seen through the central opening which is in the 120 right hand face of Fig. 2; and the third series—the Glorious Mysteries—are portrayed by the bottom row of pictures, revealed through the lowest opening located at the bottom of the center face in Fig. 1. Hence, when the use of any particular one 125 of these groups is in contemplation it is but necessary to rotate the housing 16 until the desired window is brought squarely to the front (which may be any side of the base, 130

10, at the option of the user) and then operate the handle 124 of lever 12 as described until the first picture of the required group appears at the opening and 5 thereafter the views are, slowly or rapidly, as desired, successively progressed by the same means.

While I have shown in the drawings the superstructure or main body portion of the 10 apparatus in the form of a vertical prism, it is obvious that this section, with its doors, view windows, pictures and tablets might be constructed in the form of a cylinder and the number, order and arrangement of these 15 appurtenances varied, without departing from the spirit of my invention, and that the outlines of the pictures with the openings through which they are viewed, as well as the tablets or printed or embossed reading matter could, for example, be circular, elliptical or arched, instead of rectilinear, without departing therefrom.

Having thus explained the nature of my 20 invention and described and shown a way of constructing the same, without attempting to set forth all the forms in which it could be made or all the modes of its use, I claim—

1. In a device of the character described, the combination of a stationary base, a 25 rotatable frame thereon, a series of translucent pictures arranged in divers groups, each group extending around said frame in a horizontal line at a different height, a rotatable housing on said base concealing all 30 of said pictures except one of each group, said pictures thus exposed being positioned at equidistant openings around said housing, reading matter of artistic typography 35 permanently impressed upon said housing, means to rotate said frame in one direction only, means to illuminate said pictures by transmitted light, and means to rotate said housing on said base.

2. In a device of the character described, the combination of a stationary base, a rotatable frame centered thereon, a series of 40 translucent religious pictures arranged in divers groups, said groups extending horizontally around said frame at different heights, a rotatable housing on said base concealing all of said pictures except one of each group, said pictures thus exposed being positioned at equidistant openings around said housing, prayers in artistic typography 45 permanently impressed upon said housing, means to rotate said frame in one direction only, a candle holder and candle within said frame, means to provide ventilation therefor, and means to rotate said 50 housing on said base in either direction.

3. In a device of the character described, the combination of a stationary base, a

rotatable frame centered thereon, a series of translucent pictures illustrating the "Rosary" arranged in three groups called, respectively, the "Joyful," "Sorrowful," and "Glorious" mysteries, each group extending horizontally around said frame at a different elevation, a housing rotatable on said base, concealing all of said pictures 65 except one of each group, said pictures thus exposed being positioned at equidistant openings around said housing, prayers in artistic typography permanently impressed upon said housing, means to rotate said frame in one direction only, means to illuminate said pictures by transmitted light, and means to rotate said housing.

4. In a device of the character described, the combination of a square stationary base, 70 a prism shaped rotatable frame centered thereon, a series of translucent pictures illustrating the "Rosary" arranged in three groups called, respectively, the "Joyful," "Sorrowful," and "Glorious" mysteries, each 75 group extending horizontally around said frame at a different elevation, a prism shaped rotatable housing on said base concealing all of said pictures except one of each group, said pictures thus exposed being positioned at equidistant openings around said 80 housing, prayers in artistic typography permanently impressed upon said housing, means to illuminate said pictures by transmitted light, means to rotate said frame in 85 one direction only, and means to rotate said housing in either direction.

5. In a device of the character described, the combination of a square base, a prism shaped rotatable frame centered thereon, a 90 series of translucent pictures illustrating the "Rosary" arranged in three groups called, respectively, the "Joyful," "Sorrowful," and "Glorious" mysteries, each group extending horizontally around said frame at a different elevation, a prism shaped rotatable housing on said base concealing all of said pictures except one of each group, said pictures thus exposed being positioned at equidistant openings around said housing, 95 prayers in artistic typography permanently impressed upon said housing, a candle-holder and a candle within said frame, means to provide ventilation for said candle, means to rotate said frame in one direction only, and means to rotate said housing in 100 either direction.

Signed at Philadelphia, Pennsylvania, this sixth day of June, A. D. 1922.

JOSEPH I. COMBER.
